VARIABLE PITCH PROPELLER

Percy Horrocks, Hyde Park, N. Y.

Application June 26, 1936, Serial No. 87,500

3 Claims. (Cl. 170—163)

The present invention relates to aircraft propellers and more particularly to mechanisms associated with a propeller by which the pitch of the blades thereof may be varied.

5 The primary object of the invention is to provide a simple and rugged mechanism of a minimum number of parts adapted for construction within the hub of a propeller whereby the blade pitch may be adjusted to any desired angle at 10 the will of the pilot.

Another object resides in the novel arrangement of certain elements of the mechanism comprising the invention which, in addition to providing blade pitch varying means, affords reinforcing members for the propeller blades so as, during rotation of the propeller, to counteract the centrifugal force and bending stresses imparted to the blades.

A further object of the invention is to provide 20 a propeller pitch change actuating mechanism, the same being particularly adapted for symmetrical arrangement about the axis of rotation of the propeller thereby obviating the occurrence of vibration and other such detrimental reactions resulting from high speed operation of the propeller.

The invention will be fully and comprehensively understood from a consideration of the following detailed description when read in connection 30 with the accompanying drawings which form part of the application.

In the drawings:

Figs. 1 and 2 are side and rear elevational views, respectively, of the variable pitch propeller directed to illustrate the general arrangement of the same.

Fig. 3 is a fragmentary sectional view of the propeller hub portion taken on the planes indicated by the staggered line 3—3 of Fig. 1 and 40 illustrating the actuating mechanism for effecting the blade pitch change; and

Fig. 4 is a transverse sectional view taken on line 4—4 of Fig. 3.

Referring now to the drawings for a more detailed description thereof, the numeral 5 indicates the drive shaft by which the propeller is rotated, the same being secured to the propeller hub 6 by suitable means such as that illustrated in Fig. 4. Onto the hub 6 is formed a cylindrical 50 casing 7, the same including at its forward end a removable cover 8.

In the cylindrical wall of the casing 7 are journaled a plurality of propeller blades 9 preferably secured for axial rotation in bearing sleeves 55 10 integral with the casing 7. The blades 9 are

retained for rotation within the bearings 10, preferably in the manner shown in Fig. 3 in which the blade spindle 11 includes a thrust collar 12 adjustably secured within the bearing 10 by a threaded sleeve 13.

The means for rotating each of the propeller blades 9 to effect the pitch change thereof comprises a pull rod 14 extending from within the casing 7 and substantially longitudinal to the blade 9, being anchored at the tip 15 thereof. 10 The pull rod 14 is slidably retained in a slide bearing 16, the latter being secured to the blade 9 preferably at the widest portion of the blade and adjacent the trailing edge of same. Each of the pull rods 14 extending to within the casing 15 7 thru suitable apertures 17 in the wall thereof are pivotally anchored, as indicated at 18, to the end wall of the casing 7.

As hereinafter described, the variation of the blade pitch is effected by exerting a pull on each 20 of the rods 14, which pull is effected by means comprising a pinion gear 19 disposed centrally in the casing 7. The pinion gear 19 is carried on and rotated by a shaft 20, which shaft extends axially from the drive shaft 5 and is mounted for 25 rotation independently of same in a central bore of the drive shaft 5. It is, of course, to be expressly understood that the shaft 20 positioned concentrically within the drive shaft 5 can be moved relatively thereof during operation of the 30 propeller. That is to say, the shafts 5 and 20 during use can be rotated at the same speed or at slightly different speeds whereby relative rotation takes place. The actuating means for the pull rods 14 also includes a series of sector gears 35 21, each of which is mounted for rotation about a stud 22 secured to the casing 7. Each of the sector gears 21 is formed in an arcuate flange 23 on which is carried an internal gear 24. The web of each of the sector gears 21 has a cut-out 40 portion 25 to permit the shaft 20 to extend there-thru.

It will be observed that the rotation of the pinion gear 19 actuated by means of the shaft 20 will impart to each of the sector gears 21 an 45 angular movement. This movement is transmitted to the pull rod 14 by having the mentioned rod secured to the sector gear 21 by means of a lug 26 projecting from a corner of the sector gear 21. The rod 14 is fixed to the lug 26 by a series 50 of clamping elements 27 extending thru the latter.

In considering the operation of the mechanism to effect a pitch change it will be noted that in view of the eccentricity of the slide bearing 16 55

on the blade 9 that the exertion of a substantially transverse pull on the rod 14 will cause the trailing edge of the blade 9 to be moved so as to increase the pitch of the propeller blade 9. This pull on the rod 14 is applied between the slide bearing 16 and the anchor point 18, which section is normally in a straight line. It will be noted that by flexing the mentioned section the distance between the point 18 and the bearing 16 will be foreshortened and in consequence the bearing 16 will be moved in the manner to cause the rotation of the propeller blade 8.

To return the propeller blade to its normal pitch the pinion gear 19, being reversed, will cause the rod 14 to be brought to a straight line form during which the rod 14 by a thrust action pushes the bearing 16 to its normal position. In accordance with the theory of operation by which the pull rod 14 functions to change the pitch of the propeller blade 9 the action occurring takes place substantially between the bearing 16 and the pivotal anchor 18 of the pull rod 14. Accordingly, the bearing 16 may be considered as forming a fixed connection of the rod 14 to an eccentric portion of the blade 9. However, in order that the rod 14 serve as a reinforcing element to the blade 9, same is arranged to slide within the bearing 16 and is extended longitudinally of the blade 9 to be anchored at the tip 15 thereof. This arrangement is provided so that the rod 14 may serve as a strengthening element to the blade 9 by counteracting a centrifugal force imparted to same during the high speed rotation of the propeller.

Referring to Fig. 3, it will be observed that the pivotal anchor 18 of the rod 14 is substantially adjacent the point of rotation 22 of the sector gear 21 and since the rod 14 is fixedly secured to a corner of the sector gear 21 by the lug 26, that section of the rod 14 between the lug 26 and anchor 18 will move in unison with the adjacent edge of the sector gear 21 and may accordingly be omitted. However, the arrangement illustrated is preferred so that in the event of failure of any of the actuating members preceding the rod 14, the latter will merely move to its normal straight line position and thus permit the blade 9 to return to its normal pitch.

It is to be understood that this improvement is capable of extended application and is not confined to the exact showing of the drawings

nor to the precise construction described and, therefore, such changes and modifications may be made therein as do not affect the spirit of the invention nor exceed the scope thereof as expressed in the appended claims.

What is claimed as new is:

1. A variable pitch propeller comprising in combination, a propeller hub, a series of blades extending from said hub and rotatably mounted therein, a pull rod for each of said blades connected to an eccentric point thereof, said pull rods converging to said hub and actuating means associated with said hub for tensioning said pull rods so as to rotate said blades, said actuating means comprising a rotary pinion gear and a series of sector gears in mesh with said pinion gears, each of said sector gears being operatively connected to one of said pull rods for tensioning the same so as to rotate said blades.

2. A variable pitch propeller comprising in combination, a propeller hub, a drive shaft secured to said hub, a series of blades extending from said hub and rotatably mounted therein, a pull rod for each of said blades connected to an eccentric point thereof, said pull rods converging to said hub and actuating means associated with said hub for tensioning said pull rods so as to rotate said blades, said actuating means comprising a rotary pinion gear and a series of sector gears in mesh with said pinion gears, each of said sector gears being operatively connected to one of said pull rods for tensioning the same so as to rotate said blades.

3. A variable pitch propeller comprising in combination, a propeller hub including a hollow casing, a series of blades journaled for rotation on said hub casing, a pull rod for each of said blades connected to an eccentric point thereof, said pull rods converging to said hub casing and terminating within same, and actuating means associated with said hub casing for tensioning said pull rods so as to rotate said blades, said actuating means comprising a rotary pinion gear and a series of sector gears pivotally mounted within said casing and in mesh with said pinion gears, each of said sector gears being operatively connected to one of said pull rods for tensioning the same so as to rotate said blades.

PERCY HORROCKS.
